(57) **CLAIM**

The ornamental design for a bib, as shown and described.

DESCRIPTION

FIG. 1 is a perspective rear view of a bib, showing my new design.

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a perspective view thereof, in one possible environment.

The broken lines shown in FIGS. 1-7 are understood to represent stitching. The broken lines showing a child and feeding bottle in FIG. 8, illustrates the use of the article, and forms no part of the claim.
